(57) **CLAIM**

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is an enlarged view of the encircled portion 9 in FIG. 1;

FIG. 10 is an enlarged view of the encircled portion 10 in FIG. 4;

FIG. 11 is an enlarged view of the encircled portion 11 in FIG. 4;

FIG. 12 is an enlarged view of the encircled portion 12 in FIG. 6;

FIG. 13 is an enlarged view of the encircled portion 13 in FIG. 8; and,

FIG. 14 is an enlarged view of the encircled portion 14 in FIG. 8.

The evenly-dashed broken lines on the strap feature of the case for electronic device design in FIGS. 1, 2, 3 and 8 illustrate surface ornamentation in the form of the outline of a truncated letter "S" that forms no part of the claimed design. The remaining evenly-dashed broken lines in the figures depict portions of the case for electronic device that form no part of the claimed design.

The dot-dash broken lines encircling portions of the claimed design that are illustrated in enlargements form no part of the claimed design.
